CLAIM

The ornamental design for a dunnage bag valve, as shown and described.

DESCRIPTION

FIG. 1 is a perspective view of a dunnage bag valve showing my new design;

FIG. 2 is a left side elevational view thereof;

FIG. 3 is a right side elevational view thereof;

FIG. 4 is a front side elevational view thereof;

FIG. 5 is a top side plan view thereof;

FIG. 6 is a rear side elevational view thereof; and,

FIG. 7 is a perspective view thereof showing my new design in its assembled structural appearance.
